PACKAGE AND METHOD OF PRODUCING
THE SAME

Donald R. Grant, Canajoharie, and Edward J. Hambrecht, Palatine Bridge, N. Y., assignors to Beech-Nut Packing Company, Canajoharie, N. Y., a corporation of New York

Application December 16, 1931, Serial No. 581,316

13 Claims. (Cl. 93—2)

One method at present employed in the wrapping of hard or cooked candies in stacks or rolls, has been to first wrap the roll with a waxed paper wrapper which is wound around the peripheral surface of the roll, and its ends tucked in over the ends of the roll. After the roll has thus been completely wrapped with the waxed paper, a sheet of foil is similarly wrapped about the waxed paper wrapper and its ends tucked in over the 5 tucked in ends thereof. Suitable degrees of heat and pressure are then applied over the entire cylindrical surface and tucked ends of the foil wrapper so as to cause the wax of the paper wrapper to melt and when allowed to cool, tightly 10 seal the longitudinal seam and the end tucks of the paper wrapper and to cause the paper and foil wrappers to adhere firmly together substantially throughout their contacting surfaces.

With this method as heretofore commercially 20 employed, it has been found that as the waxed paper wrapper contacts directly with the candies, when the wax is melted as above described and allowed to cool to seal the package, wax is likely to adhere to the candy, especially to the edges 25 thereof which of course, is objectionable.

One of the objects of the present invention is to provide a method of wrapping articles, such as hard or cooked candies, which overcomes the disadvantage of the method heretofore employed 30 as above described.

Another of the objects of the invention is to provide a novel and improved package, and method of producing the same.

The several features of the invention, whereby the above-mentioned and other objects may be attained, will be readily understood from the following description and accompanying drawings, in which:

Figure 1 is a view in perspective of a waxed 40 paper wrapper and an unwaxed paper wrapper which may be employed in our improved package;

Fig. 2 is a similar view showing the two wrappers partially wrapped about the peripheral surface of a stack or roll of hard or cooked candies;

Fig. 3 is a similar view showing the wrappers completely wound about the peripheral surface of the roll of candies;

Fig. 4 is a similar view showing the two paper wrappers as thus applied tucked in over the ends 50 of the roll;

Fig. 5 is a view in perspective of the completed package;

Fig. 6 is a view similar to Fig. 2 but showing the 55 wrappers partly applied in a different form of package;

Fig. 7 is a view in perspective of the completed package of the form shown in Fig. 6;

Fig. 8 is a rear view of a portion of a wrapping machine which may be employed in carrying out our improved method;

Fig. 9 is a sectional view taken on the line 9—9 of Fig. 8; and

Fig. 10 is a diagrammatical view showing the arrangement of certain wrapping devices of the machine near the start of the operation of wrapping a roll of candies.

In wrapping a stack or roll of articles 2, such as hard candies that are in the form of circular disks, in accordance with our improved method, a sheet of waxed paper 4 and a sheet of unwaxed 15 paper 6, which preferably is glassine paper, are positioned one upon the other with one end of the glassine paper projecting slightly beyond the corresponding end of the waxed paper. The glassine wrapper is of slightly greater width than 20 the length of the roll of articles, and the waxed paper wrapper is of greater width than the glassine paper. The two wrappers are then wrapped slightly more than two complete turns around the roll so that their edges overlap slightly as 25 shown, the glassine wrapper being on the inside and its longitudinal edges projecting slightly beyond the ends of the roll. The projecting ends of the two wrappers are then tucked in over the ends of the roll, this operation crimping over the 30 slightly projecting ends of the glassine wrapper, the projecting ends of the waxed paper wrapper preferably being tucked in by radially extending tucks. When the roll has thus been completely wrapped with the two wrappers, a sheet 8 of foil 35 is then first wrapped about the peripheral surface of the paper wrappers and then its ends are tucked in over the tucked in ends of the waxed paper wrapper. The foil wrapper instead of being wrapped twice around the article as is preferably the case with the paper wrappers as above described, is wrapped approximately one and one-quarter turns around the roll, and the overlapping portions thereof are arranged so as to overlie the outer longitudinal edges of the paper wrappers. 45

After the roll has been thus wrapped with both the paper and foil wrappers, a suitable degree of heat is applied, preferably to the entire area of the peripheral surface and tucked in ends of the foil wrapper to melt the wax of the paper wrapper. 50 The package is then subjected to a rolling and pressing action, and the ends of the package are subjected to pressure. Such operations are preferably continued until the wax has become thoroughly cool or set. Such rolling and pressing 55

action is preferably of such a nature as to tend to cause the wrappers to more or less tightly engage or grip the roll, and to insure that the overlapping peripheral portions of the paper wrappers are thoroughly sealed and the foil wrapper sealed or affixed to the waxed paper wrapper throughout the peripheral area thereof. The pressing operation applied to the ends of the package is preferably such as to insure that the tucked 5 in ends of both the waxed paper wrapper and the foil are tightly secured or ironed flat against the ends of the roll, which insures that the successively overlapping tucks of the paper wrapper are securely and tightly sealed together and that the 10 end tucks of the foil wrapper are securely sealed to the end tucks of the waxed paper wrapper. 15

By wrapping the roll of candies in accordance with our improved method, it will be apparent that the peripheral surface and edges of the 20 candies are thoroughly protected from the melted wax during the heat-sealing operation. The inner end of the glassine wrapper insures against the wax working over the inner edge of the waxed paper wrapper into contact with the candies. Also, the projecting longitudinal edges or convolutions of the glassine wrapper insures against the melted wax coming into contact with the outer edges of the outermost end candies. 25

If desired, at the completion of the heat-sealing 30 operation, the usual label 7 may be secured about the package.

In the form of package illustrated in Figs. 6 and 7 instead of the hard candies being arranged in stacks or rolls, a series of three single candies 35 2' are arranged in edge to edge relation in a row. In wrapping the articles as thus arranged, the glassine paper 6' and the waxed paper 4' are together wrapped about the row of articles with the glassine innermost, with its inner end projecting 40 slightly beyond the inner end of the waxed paper and its longitudinal edges projecting slightly beyond the outer edges of the articles, as shown in Fig. 6. When the two wrappers have been completely wrapped two or more times about the row 45 of articles, the projecting ends of the waxed paper wrapper may be suitably folded over the ends of the article. The package may be sealed by the application of heat to the waxed paper wrapper. When the package has thus been heat-sealed, a 50 label 10 may be placed around the package.

In this form of package also it will be apparent that the articles are thoroughly protected from the melted wax during the heat sealing.

The machine illustrated in Figs. 8, 9 and 10 is 55 of the type of the one described and claimed in the patent to Harry E. Townsend, "Wrapping machine", No. 1,813,974, dated July 14, 1931. As shown, this machine is provided with lower and upper wrapping rolls 12 and 14, respectively, arranged horizontally in the same vertical plane for receiving the article to be wrapped between them, and is further provided with retaining rolls 16 60 for engaging opposite sides of the article so as to retain the article between the wrapping rolls 65 during the wrapping operation. The wrapping rolls serve to wind the wrapper about the article, the ends of the wrapper projecting beyond the ends of the article. Tucking members 18 are arranged adjacent the ends of the lower roll for tucking in the projecting ends of the wrapper over the ends of the article after the wrapper has 70 been wound about the article.

The wrapping material from which the wrappers 75 are formed is fed downwardly by means of

feed rolls 20, between cutting off knives 22. A suitable article conveying device 30 conveys the articles to the wrapping rolls. As each article is conveyed to the wrapping rolls, it engages the portion of the wrapper that projects below the 5 knives 22 and carries the same therewith to a position between the rolls. The knives then cut off a length of the wrapping material and the wrapping rolls and associated parts operate to wrap the wrapper about the article, the wrapping material during this time being fed downwardly by the rolls 20 to present a length thereof to the next article to be wrapped. At the completion of the 10 wrapping of each article with paper, the wrapped article may be delivered to similar wrapping 15 mechanism for placing a foil wrapper thereon.

Except for the wrapper feed rolls 20, the parts of the machine above described may be and preferably are of the construction of the corresponding parts of the machine of said Patent No. 20 1,813,974, to which reference may be had for a full and complete description of the same.

In accordance with the present invention, two strips 24 and 26 of wrapping material are fed between the feed rolls and between the knives 22, 25 the former being of waxed paper and the other of glassine. These two strips are separately drawn from supply rolls 28 mounted on stud shafts 29 on the machine frame. Each of the supply rolls 30 28 is frictionally held from overrunning by a plate-like arm 31, the lower end of which is pivoted on a rod 32 and its upper end is pressed against the periphery of the roll by a coiled spring 34.

The feed roll 20 that engages the glassine strip 35 26 is slightly larger in diameter than the other feed roll, the two rolls being driven at the same speed. With this construction the glassine strip 26 is fed downwardly slightly faster than the waxed paper 24 so that when the lower end portions of the two strips are positioned across the 40 path of the article to be wrapped, the end of the glassine strip projects slightly beyond the end of the waxed paper strip. The portions of the two strips below the knives are carried by the article to the wrapping devices, in the same manner as the corresponding portion of the single wrapping strip of said patented machine. The knives 22 then cut off the projecting lengths of 45 the two strips to form superposed wrappers such as illustrated in Figs. 1 to 4 of the drawings, the 50 wrapping devices then wrapping the article in the glassine and waxed paper wrappers as above described.

As will be evident to those skilled in the art, our invention permits various modifications without departing from the spirit thereof or the scope of the appended claims.

What we claim is:

1. The method of wrapping an article which 60 comprises applying a wrapper of waxed paper and a wrapper of unwaxed paper about the article with the unwaxed paper on the inside and with its inner end projecting beyond the inner end of the waxed paper wrapper, positioning the wrappers in said predetermined relation previously to applying them to the article, applying a wrapper of foil over the paper wrapper, and applying heat to the foil to cause the wax of the waxed paper wrapper to secure the wrappers about the article. 65

2. The method of wrapping an article which 70 comprises applying a wrapper of waxed paper and a wrapper of unwaxed paper about the article with the unwaxed paper on the inside and with its inner end projecting beyond the inner end of 75

the waxed paper wrapper, positioning the wrappers in said predetermined relation previously to applying them to the article, and applying heat to the waxed paper wrapper to cause the 5 wax thereof to secure the wrappers about the article.

3. The method of wrapping an article of cylindrical form which comprises wrapping about the peripheral surface of the article a wrapper of unwaxed paper and a wrapper of waxed paper with the unwaxed paper on the inside and with its inner end projecting beyond the inner end of the waxed paper, the ends of the unwaxed paper projecting a slight distance beyond the ends of 10 the article and the ends of the waxed paper projecting a distance beyond the ends of the unwaxed paper, tucking in the ends of the wrappers over the ends of the article so as to completely enclose the article, similarly wrapping a sheet of foil over 15 the paper wrappers so as to completely enclose them, and applying suitable degrees of heat and pressure to the foil wrapper to cause the wax of the waxed paper wrapper to secure the wrappers about the article.

25 4. The method of wrapping an article which comprises wrapping about the peripheral surface of the article a wrapper of unwaxed paper and a wrapper of waxed paper with the unwaxed paper on the inside and with its inner end projecting beyond the inner end of the waxed paper, the ends of the unwaxed paper projecting a slight distance beyond the ends of the article and the ends of the waxed paper projecting a distance beyond the ends of the unwaxed paper, folding the ends 30 of the wrappers over the ends of the article so as to completely enclose the article, and melting the wax of the waxed paper wrapper to secure the wrappers about the article.

5. The method of wrapping an article of cylindrical form which comprises feeding a strip of waxed paper and a strip of unwaxed paper of 40 narrower width longitudinally, the unwaxed paper being fed at a slightly faster rate of speed than the waxed paper, positioning the advancing end portions of the two strips together with the unwaxed strip arranged centrally of the waxed strip, cutting off forward end lengths of the two strips to form superposed wrappers with the advancing end of the unwaxed paper wrapper projecting slightly beyond the corresponding end of the waxed paper wrapper, winding the two wrappers about the peripheral surface of the article with the unwaxed paper wrapper on the inside 45 and its ends projecting slightly beyond the ends of the article, tucking in the ends of the wrapper over the ends of the article, applying a foil wrapper over the paper wrappers, and tucking the ends thereof over the tucked in ends of the paper wrapper, and applying heat to the surface of the 50 foil wrapper to cause the wax of the waxed paper wrapper to secure the wrappers about the article.

6. The combination of an article of cylindrical form, a wrapper of waxed paper and a wrapper of unwaxed paper wrapped about the peripheral surface of the article with the unwaxed paper on the inside and its ends projecting slightly beyond the ends of the article, its inner end projecting slightly beyond the inner end of the waxed paper 55 wrapper, and the ends of the two wrappers tucked over the ends of the article, and a wrapper of foil similarly wrapped about the paper wrappers as thus applied with the wax of the waxed paper wrapper securing the wrappers about the article.

7. The combination of an article having opposed ends, a wrapper of waxed paper and a wrapper of unwaxed paper wrapped about the article with the inner end of the unwaxed paper wrapper projecting a distance beyond the end of the waxed paper wrapper, and a wrapper of foil similarly wrapped about the paper wrapper as thus applied with the wax of the waxed paper wrapper securing said wrappers about the article. 5

8. In a package comprising an article having an inner wrapper of waxed paper and an outer wrapper of foil with the wax of the paper wrapper securing the wrappers about the article, the improvement which comprises a wrapper of unwaxed paper inside of the waxed paper wrapper with its inner end projecting a distance beyond the 10 inner end of the waxed paper wrapper.

9. In a package comprising an article having a waxed paper wrapper with the wax thereof securing the wrapper about the article, the improvement which comprises a wrapper of unwaxed paper inside of the waxed paper wrapper with its inner end projecting a distance beyond the 15 inner end of the waxed paper wrapper.

10. In a package comprising an article of cylindrical form, and a wrapper of waxed paper wrapped about the peripheral surface of the article with its ends tucked in over the ends of the article, and with the wax thereof securing said tucked in ends in position, the improvement 20 which comprises a lining of unwaxed sheet material wrapped about the peripheral surface of the article and arranged between said surface and the outer wrapper with the ends of said lining bent over the end edges of the article and 25 held in position by said tucked in ends of the outer wrapper.

11. In a package comprising an article of cylindrical form, and a wrapper of waxed paper wrapped about the peripheral surface of the article with its ends tucked in over the ends of the article, and with the wax thereof securing said tucked in ends in position, the improvement 40 which comprises a lining of unwaxed sheet material wrapped about the peripheral surface of the article and arranged between said surface and the outer wrapper with the ends of said lining bent over the end edges of the article and 45 held in position by said tucked in ends of the outer wrapper, and with the inner edge of said lining projecting beyond the inner edge of the waxed paper wrapper.

12. The method of wrapping an article of cylindrical form which comprises winding a wrapper of waxed paper and a wrapper of unwaxed paper 55 about the peripheral surface of the article with the unwaxed paper on the inside and its longitudinal edges projecting slightly beyond the ends of the article and with the longitudinal edges of the waxed paper projecting beyond the ends of the article a distance of at least the length of the radius of said ends, tucking in said longitudinal edge portions of the waxed paper wrapper over the ends of the article, and applying heat and 60 pressure to the tucked in portions of the waxed paper wrapper to cause the wax thereof to secure 65 said portions in position.

13. The method according to claim 10 which includes the additional step of positioning the inner unwaxed paper wrapper with its inner end 70 projecting beyond the inner end of the waxed paper wrapper.

DONALD R. GRANT.
EDWARD J. HAMBRECHT.
